UNITED STATES PATENT OFFICE

OTTO H. HARTMANN, OF CASSEL-WILHELMSHOHE, GERMANY, ASSIGNOR TO SCHMIDT'SCHE HEISSDAMPF-GESELLSCHAFT MIT BESCHRANKTER HAFTUNG, OF CASSEL-WILHELMSHOHE, GERMANY, A CORPORATION OF GERMANY

SUPERHEATING OF INTERSTAGE STEAM

Application filed July 11, 1928, Serial No. 291,802, and in Germany July 29, 1927.

My invention relates to an arrangement for the superheating of interstage steam, more particularly in marine steam plants, by means of a heat carrier in the form of steam in marine boilers with a return for the hot gases. The superheating of the interstage steam of multi-stage steam engines by means of high-pressure heating steam serving as a heat carrier, which circulates in a closed circulating system, has certain known advantages and installations are known in which the generator of the said high-pressure heating steam is incorporated in the furnace of marine boilers provided with a return for the hot gases. An especially suitable installation of this character is the installation in which the auxiliary boiler for the generation of the high-pressure heating steam is incorporated in the rear wall of the reversing chamber in the form of a radiation boiler (see Figures 1 and 2 of the U. S. Patent No. 1,618,230, filed Dec. 15, 1920, and granted to Wilhelm Schmidt). The advantage of such an arrangement lies mainly in this that for the superheating of interstage steam by high-pressure condensing fresh steam it is sufficient to produce comparatively small quantities of heating steam and that consequently the heating surface to be built in can be made comparatively small. This heating surface absorbs from the heating gases only so much heat that a sufficient quantity of heat still remains available for the required high superheating of the working steam produced in the main boiler, which superheating is effected in the heating tubes of the marine boiler which are provided with superheating tubes. The comparatively small reduction in the superheating of the working steam caused by the building in of the heating elements of the high-pressure auxiliary boiler is more than compensated by the advantage gained by the high superheating of the interstage steam in the low pressure stage.

While the arrangement with a radiating boiler in the reversing chamber above referred to can be carried out without any difficulty in the case of new installations, it is difficult to find a satisfactory solution in the case of

existing marine boiler installations in order to improve their output in a known manner by constructing into the existing engine a low pressure stage, more particularly an exhaust-steam turbine, and superheating the interstage steam. The obvious solution, of building the heating coils of the high-pressure auxiliary boiler in the smoke box attached to the chimney, in which there is sufficient space for accommodating a comparatively large heating surface, does not come into question since the heating gases before arriving at this point have supplied too much heat to the heating surface of the main boiler and to the superheating elements built in the heating tubes.

According to my present invention the problem is satisfactorily solved by the heated part of the auxiliary steam generator lying in the reversing chamber being constructed in a manner well known in connection with superheaters, viz., as heating coils with U-shaped return bends which are inserted from the outside into the reversing chamber. In single ended Scotch boilers, the U-shaped bends of the heating coils are inserted through flanged sockets which are provided after removal of the staybolts between the end of the boiler and the wall of the reversing chamber. In the case of the double-ended Scotch boilers, according to one suitable form of construction, the heating coils of the auxiliary boiler which generates the heating steam for the superheating of the interstage steam are inserted with their reversing ends into the reversing chamber, which lies in the centre, through a portion of the heating tubes of the working boiler, the remaining portion thereof being provided with the superheating coils of the working boiler.

The accompanying drawings illustrate diagrammatically and by way of example the two forms of construction above referred to, Figures 1 and 2 being a sectional elevation and end view respectively of the first form of construction and Figure 3 a sectional elevation of the second form of construction.

Referring to Figures 1 and 2 which illustrate an existing single-ended Scotch boiler, the staybolts between the end 1' of the boiler

and the wall 2' of the reversing chamber 2 are replaced by flanged sockets which act as strengthening members in the place of the staybolts whilst they allow at the same time the tubes of the heating coils 4 of the auxiliary boiler to be passed through. The auxiliary boiler is provided with an upper drum 5 and a lower water collecting drum 6 and is partly filled with the heat carrier, for instance distilled water. The water circulates in a closed cycle through the heating coils of the interstage superheater 7 provided on the engine, in the direction of the arrows, thereby changing its physical state, the condensate being returned through the pipe 8 into the drum 5. In normal operation the whole of the heating steam passes through the pipes 9 and 10 and over an automatically acting stop valve 11 into and through the interstage superheater 7. However, when the pressure and temperature in the auxiliary boiler exceeds the normal values, the valve 11 opens automatically, so that the excess of heating steam passes in a known manner through a heating coil 12, thereby giving up its excess heat to the water of the working boiler 1. The superheater 13 for the working steam generated in the boiler 1 is built in a known manner in the heating tubes 14 of the working boiler. After the heating gases have passed through the flue tube 15, they give up a portion of the heat, which they still contain in large quantity, to the heating coils 4 of the auxiliary boiler which project into the reversing chamber 2, so that the heating surface of the auxiliary boiler required for the interstage superheating is comparatively small. This permits the heating surface required for the auxiliary boiler to be subsequently incorporated in a simple manner in an existing single-ended marine boiler. The places of insertion of the heating coils are made air-tight in a suitable manner, for instance, by means of divided plates with asbestos insertions.

In the case of a double-ended Scotch boiler, such as illustrated in Figure 3, the carrying out of the invention is even more simple in so far as a portion of the heating tubes 14 of the boiler can be used for the passage of the heating coils of the auxiliary boiler, in order to permit the return bends of the heating coils to project into the reversing chamber 2. Although in this form of construction the heating coils are longer and pass through some of the heating tubes of the boiler, in which otherwise the superheating tubes for the superheating of the working steam would be accommodated, this is only an apparent disadvantage, when it is borne in mind that by incorporating an exhaust steam turbine and providing for the superheating of interstage steam by means of high-pressure fresh steam, the steam consumption is reduced to such an extent that the reduced superheating

surface more than suffices for the smaller amount of working steam to be generated per hour. Otherwise the construction is the same as that shown in Figure 1, for which reason the same reference letters have been used in both drawings and the arrangement need not be further described. 70

Having now particularly described and ascertained the nature of my said invention and in what manner the same is to be performed. 75 I declare that what I claim is:

1. An arrangement for the superheating of interstage steam in marine steam boilers provided with a reversing chamber for the hot gases and having live steam superheater elements arranged in its heating tubes, by means of a heat carrier in the form of steam which circulates in a closed cycle through its steam generator and the heating coils of the interstage superheater and which is produced by an auxiliary steam boiler having its heated part lying in the reversing chamber, the said heated part projected into the reversing chamber from the outside thereof. 85

2. An arrangement as claimed in claim 1 used in connection with double-ended Scotch boilers, in which the heated part comprises coils having U-shaped return bends which are inserted into the reversing chamber lying in the centre of the working boiler through a portion of the heating tubes of the working boiler, the other portion of which accommodates the superheating coils of a live steam superheater for the working steam. 95

3. An arrangement for the superheating of interstage steam in marine boilers provided with a reversing chamber for the hot gases and having live steam superheater elements arranged in its heating tubes, by means of a heat carrier in the form of steam which circulates in a closed cycle through its steam generator and the heating coils of an interstage superheater and which is produced by an auxiliary steam boiler having its heating part lying in the reversing chamber, the said heated part being constructed in the form of heating coils having U-shaped return bends, each of the U-shaped return bends being introduced into the reversing chamber through an individual opening in the wall thereof. 105

In testimony whereof I have affixed my signature.

OTTO H. HARTMANN.
